CLAIM

The ornamental design for a holder for a tissue box, as shown and described.

DESCRIPTION

FIG. 1 is a front, side and top perspective view of a holder for a tissue box, showing my new design in open condition; FIG. 2 is a top plan view of the holder for a tissue box, showing my new design in closed condition;

FIG. 3 is a bottom plan view thereof;

FIG. 4 is a front elevation view thereof;

FIG. 5 is a rear elevation view thereof;

FIG. 6 is a left side elevation view thereof; and,

FIG. 7 is a right side elevation view thereof.
